Botanical designation: *Chrysanthemum X morifolium*.
Cultivar denomination: 'DLFSALM2'.

**CROSS-REFERENCED TO CLOSELY-RELATED
APPLICATIONS**

Title: Varieties of *Chrysanthemum* Plants
Inventor/Applicant: Arie Gerard Post
Filed: Mar. 20, 2019
Ser. No. 62/919,611

Inventor/Applicant hereby claim the benefit of this provisional U.S. Patent Application.

**STATEMENT REGARDING PRIOR
DISCLOSURES BY INVENTOR/APPLICANT &
ASSIGNEE**

An European Community Plant Breeder's Rights application for the instant plant was filed by the Assignee, Deliflor Royalties B. V. of Maasdijk, The Netherlands on Feb. 1, 2019, application number 2019/0358. Foreign priority is not claimed to this application.

The Inventor/Applicant and Assignee assert that no publications nor advertisements relating to sales, offers for sale or public distribution occurred more than one year prior to the effective filing date of this application. Any information about the claimed plant would have been obtained from a direct or indirect disclosure from the Inventor/Applicant and/or the Assignee. Inventor/Applicant and Assignee claim a prior art exemption under 35 U.S.C. 102(b)(1) for disclosure and/or sales prior to the filing date but less than one year prior to the effective filing date.

BACKGROUND OF THE INVENTION

The present invention relates to a new and distinct cultivar of *Chrysanthemum* plant, botanically known as *Chrysanthemum*

(57) **ABSTRACT**

A new and distinct cultivar of *Chrysanthemum* plant named 'DLFSALM2', characterized by its upright plant habit; vigorous growth habit; dark green-colored leaves; uniform flowering habit; strong upright flowering stems typically grown as a single-stem (disbudded) cut flower; large decorative-type inflorescences with light yellow-colored ray florets; and relative resistance to *Fusarium oxysporum* f. sp. *chrysanthemi* and *Verticillium dahliae*.

2 Drawing Sheets

2

mum x morifolium, typically grown as a cut flower *Chrysanthemum* and hereinafter referred to by the name 'DLFSALM2'.

The new *Chrysanthemum* plant is a product of a planned breeding program conducted by the Inventor in Maasdijk, The Netherlands. The objective of the breeding program is to create new cut flower *Chrysanthemum* plants with numerous attractive inflorescences.

The new *Chrysanthemum* plant is a naturally-occurring whole plant mutation of *Chrysanthemum x morifolium* 'Delisalma', not patented. The new *Chrysanthemum* plant was discovered and selected as a single flowering plant from within a population of plants of 'Delisalma' in a controlled greenhouse environment in Maasdijk, The Netherlands in June, 2012.

Asexual reproduction of the new *Chrysanthemum* plant by vegetative terminal cuttings since June, 2012 in Maasdijk, The Netherlands has shown that the unique features of this new *Chrysanthemum* plant are stable and reproduced true to type in successive generations of asexual reproduction.

SUMMARY OF THE INVENTION

Plants of the new *Chrysanthemum* have not been observed under all possible combinations of environmental conditions and cultural practices. The phenotype may vary somewhat with variations in environmental conditions such as temperature, daylength and light intensity, without, however, any variance in genotype.

The following traits have been repeatedly observed and are determined to be the unique characteristics of

'DLFSALM2'. These characteristics in combination distinguish 'DLFSALM2' as a new and distinct *Chrysanthemum* plant:

1. Upright plant habit; vigorous growth habit.
2. Dark green-colored leaves.
3. Uniform flowering habit.
4. Strong upright flowering stems typically grown as a single-stem (disbudded) cut flower.
5. Large decorative-type inflorescences with light yellow-colored ray florets.
10. 6. Relatively resistant to *Fusarium oxysporum* f. sp. *chrysanthemi* and *Verticillium dahliae*.

Plants of the new *Chrysanthemum* differ from plants of the mutation parent, 'Delisalma', in ray floret color as plants of the new *Chrysanthemum* have light yellow-colored ray florets whereas plants of 'Delisalma' have white-colored ray florets.

Plants of the new *Chrysanthemum* can be compared to plants of *Chrysanthemum* X *morifolium* 'Zembla Yellow', disclosed in U.S. Plant Pat. No. 14,733. In side-by-side comparisons, plants of the new *Chrysanthemum* differ primarily from plants of 'Zembla Yellow' in inflorescence size as plants of the new *Chrysanthemum* have larger inflorescences than plants of 'Zembla Yellow'.

BRIEF DESCRIPTION OF THE PHOTOGRAPHS

The accompanying photographs illustrate the overall appearance of the new *Chrysanthemum* plant showing the colors as true as it is reasonably possible to obtain in colored reproductions of this type.

The photograph on the first sheet (FIG. 1 of 2) comprises a side perspective view of a typical flowering stem of 'DLFSALM2' grown as a disbud-type cut flower.

The photograph on the second sheet (FIG. 2 of 2) is a close-up view of lower (top of the photographic sheet) and upper (bottom of the photographic sheet) surfaces of typical inflorescences (left) and leaves (right).

DETAILED BOTANICAL DESCRIPTION

The aforementioned photographs and following observations and measurements describe plants grown during the winter in ground beds in a glass-covered greenhouse in 45 Maasdijk, The Netherlands and under cultural practices typical of commercial cut *Chrysanthemum* production. Plants were initially given long day/short night treatments followed by short day/long night treatments to induce flower initiation and development. During the production of the plants, day temperatures ranged from 18° C. to 25° C., night temperatures ranged from 2° C. to 20° C. and light levels averaged 8 klux. Plants were grown as single-stem disbuds-type plants and were nine weeks old when the photographs and the description were taken. In the following description, 55 color references are made to The Royal Horticultural Society Colour Chart, 2015 Edition, except where general terms of ordinary dictionary significance are used.

Botanical classification: *Chrysanthemum* X *morifolium* 'DLFSALM2'.

Parentage: Naturally-occurring whole plant mutation of *Chrysanthemum* X *morifolium* 'Delisalma', not patented. Propagation:

Type.—Terminal vegetative cuttings.

Time to initiate roots, summer.—About six days at 65 temperatures about 24° C.

Time to initiate roots, winter.—About eight days at temperatures about 22° C.

Time to produce a rooted young plant, summer.—About twelve days at temperatures about 24° C.

Time to produce a rooted young plant, winter.—About two weeks at temperatures about 22° C.

Root description.—Fine, fibrous; typically creamy white in color, actual color of the roots is dependent on substrate composition, water quality, fertilizers, substrate temperature and physiological age of roots.

Rooting habit.—Freely branching, medium density.

Plant description:

Plant and growth habit.—Herbaceous decorative-type cut flower that is typically grown as a single stem disbuds-type; upright plant habit; vigorous growth habit and rapid growth rate.

Plant height, soil level to top of foliar plane.—About 77.7 cm.

Plant height, soil level to top of inflorescence plane.—About 82.2 cm.

Plant diameter.—About 20.7 cm.

Flowering stem length.—About 79 cm.

Flowering stem diameter.—About 6 mm.

Flowering stem internode length.—About 2.5 cm.

Flowering stem strength.—Strong.

Flowering stem aspect.—Erect.

Flowering stem texture and luster.—Moderately pubescent; slightly glossy.

Flowering stem color, developing.—Close to 144A.

Flowering stem color, developed.—Close to 146A and 146C.

Leaf description.—Arrangement: Alternate; simple.

Length: About 13 cm. Width: About 9.2 cm. Shape: Ovate to oblong. Apex: Short apiculate. Base: Attenuate. Margin: Palmately lobed, coarsely serrate; sinuses convergent and moderately deep. Texture and luster, upper surface: Moderately pubescent, not rugose; moderately velvety; matte to slightly glossy. Texture and luster, lower surface: Moderately pubescent, prominent venation; slightly velvety; matte. Venation pattern: Pinnate, reticulate. Color: Developing leaves, upper surface: Close to 137A. Developing leaves, lower surface: Close to between 138A and 147B. Fully developed leaves, upper surface: Close to between NN137A and 147A, venation, close to 146B. Fully developed leaves, lower surface: Close to 147B; venation, close to 146B to 146C. Petioles: Length: About 2.5 cm. Diameter: About 3 mm by 4 mm. Strength: Moderately strong.

Texture and luster, upper and lower surfaces: Moderately to densely pubescent; slightly glossy. Color, upper surface: Close to 146B; edges, close to 137A. Color, lower surface: Close to 146C; edges, close to 137B. Stipules: Quantity and appearance: Two leafy stipules, opposite, at the petiole attachment to the stem. Length: About 8 mm. Width: About 1.3 cm. Shape: Flabellate with incised margins. Texture and luster, upper surface: Moderately pubescent, not rugose; moderately velvety; matte to slightly glossy. Texture and luster, lower surface: Moderately pubescent, prominent venation; slightly velvety; matte. Color, upper surface: Close to between NN137A and 147A. Color, lower surface: Close to 147B.

Inflorescence description:

Appearance.—Decorative uncurved inflorescence form with oblanceolate-shaped ray florets and tubular disc florets (disc florets are inconspicuous); inflorescences borne perpendicular to peduncles and face mostly upright; ray and disc florets develop acropetally on a capitulum. 5

Fragrance.—Faintly fragrant; typical of *Chrysanthemums*.

Flowering response.—Under natural conditions, plant flower in the autumn/winter in the Northern Hemisphere; at other times of the year, inflorescence initiation and development can be induced under short day/long night conditions (at least 115 hours of darkness); uniform flowering habit and short response time, plants exposed to two weeks of long day/short night conditions after planting followed by photoinductive short day/long night conditions flower about 48 days later when grown as a disbud-type. 10

Postproduction longevity.—Good postproduction longevity; in an interior environment, inflorescences and foliage will maintain good color and substance for about two weeks; inflorescences persistent. 15

Quantity of inflorescences.—Grown as a disbud-type, all lateral inflorescences are physically removed and only the terminal inflorescence is allowed to develop; if grown as a spray-type, then typically about 23 inflorescences will develop. 20

Inflorescence size.—Diameter: Grown as a disbud type, about 11 cm and grown as a spray-type, about 9 cm. Depth (height): Grown as a disbud type, about 7.2 cm and grown as a spray-type, about 3.3 cm. Disc diameter: If present, about 5 mm. 25

Receptacles.—Height: About 7 mm. Diameter: About 1 cm. Shape: Flattened globular. Color: Close to 145C. 30

Inflorescence buds.—Height: About 1.7 cm. Diameter: About 1.2 cm. Shape: Roughly globular. Texture and luster: Distally, smooth and glabrous; proximally, slightly to moderately pubescent; slightly glossy. Color: Close to 143A to 143B; immature ray florets, close to 5B to 5C. 40

Ray florets.—Quantity and arrangement: About 240 arranged in about eight whorls. Length: About 4.5 cm; varying between 2.5 cm and 5.7 cm. Width: About 1.5 cm; varying between 0.9 cm and 1.7 cm. Shape: Oblanceolate; moderately to strongly concave and moderately carinate. Apex: Bluntly and broadly acute to obtuse. Base: Attenuate. Margin: Entire; not undulate. Aspect: Initially upright to about 90° from vertical. Texture and luster, upper surface: Smooth, glabrous; moderately velvety; matte. Texture and luster, lower surface: Smooth, glabrous; slightly velvety; slightly glossy. Color: When opening, upper surface: Close to 5C. When opening, lower surface: Close to 4C. Fully opened, upper surface: Close to 3D; towards the apex, close to 4C; venation, close to 3D and 4C; color does not change with development. Fully opened, lower surface: Close to 4D; venation, close to 4D; color does not change with development. 55

Disc florets.—Quantity and arrangement: If present, about one to three massed at the center of the 60

receptacle; disc florets inconspicuous. Length: About 7 mm. Diameter: About 1.25 mm. Shape: Lower 85% fused into a tube; upper 15% free. Apex: Narrowly acute. Margin, distally: Entire. Texture and luster, inner and outer surfaces: Smooth, glabrous; glossy. Color, when opening, inner and outer surfaces: Close to 154D; towards the apex, close to 150B to 150C and towards the base, close to 145C. Color, fully opened, inner and outer surfaces: Close to 154D; towards the apex, close to 150B to 150C and towards the base, close to 145C. 75

Involutal bracts.—Quantity and arrangement: About 22 arranged in two whorls. Length: About 1.3 cm. Width: About 6 mm. Shape: Narrowly ovate to ovate. Apex: Obtuse. Base: Cuneate. Margin: Entire. Texture and luster, upper surface: Smooth, glabrous; glossy. Texture and luster, lower surface: Moderately pubescent; matte. Color, upper surface: Close to 143A; margins, translucent and close to 157D and 200D. Color, lower surface: Close to 137C to 137D; margins, translucent and close to 157D and 200D. 80

Peduncles.—Length, terminal peduncle: About 2.4 cm. Diameter, terminal peduncle: About 5 mm. Length, third peduncle (when grown as a spray-type): About 4.5 cm. Diameter, third peduncle (when grown as a spray-type): About 3 mm. Strength: Strong. Aspect, terminal peduncle: Mostly upright. Aspect, third peduncle (when grown as a spray-type): About 50° from the flowering stem axis. Texture and luster: Densely pubescent; moderately glossy. Color: Close to 144A. 85

Reproductive organs.—Androecium: Present on disc florets only. Quantity: About five per floret. Filament length: About 2.5 mm. Filament color: Close to 145C. Anther size: About 0.5 mm by 3 mm. Anther shape: Narrowly oblong. Anther color: Close to 13A. Pollen amount: Scarce. Pollen color: Close to 14B. Gynoecium: Present on both ray and disc florets. Quantity: One per ray floret. Pistil length: About 8 mm. Style length: About 7 mm. Style color: Close to 145B. Stigma diameter: About 1.25 mm. Stigma shape: Cleft, decurrent. Stigma color: Close to 153D. Ovary color: Close to 145A. 90

Seeds and fruits.—To date, seed and fruit production have not been observed on plants of the new *Chrysanthemum*.

Pathogen & pest resistance: Plants of the new *Chrysanthemum* have been observed to be relatively resistant to *Fusarium oxysporum* f. sp. *chrysanthemi* and *Verticillium dahliae*. To date, plants of the new *Chrysanthemum* have not been observed to be resistant to pests and other pathogens common to plants grown under commercial conditions. 95

Temperature tolerance: Plants of the new *Chrysanthemum* have been observed to tolerate temperatures ranging from about -12° C. to 35° C. and to be suitable for USDA Hardiness Zones 8 to 10.

It is claimed:

1. A new and distinct *Chrysanthemum* plant named 'DLFSALM2' as illustrated and described.
